LOUIS STEINBERGER, OF BROOKLYN, NEW YORK.

HIGH-VOLTAGE STRAIN-INSULATOR.

1,160,543.

Specification of Letters Patent. Patented Nov. 16, 1915.

Application filed April 18, 1910. Serial No. 556,071.

To all whom it may concern:

Be it known that I, LOUIS STEINBERGER, a citizen of the United States, and a resident of the city of New York, borough of Brooklyn, in the county of Kings and State of New York, have invented a new and Improved High-Voltage Strain-Insulator, of which the following is a full, clear, and exact description.

10 My invention relates to insulators, for high voltage electric conductors to be used in various relations and for various purposes, and more especially to strain insulators for use on transmission lines, and for 15 guy wires or cables employed as stays for towers or for poles, masts, and other supports used in wireless telegraphy and telephony as well as in ordinary commercial work.

I seek among other things to provide an 20 insulator which is compact and simple in construction, low in cost, and capable of withstanding a considerable mechanical stress and very high voltages; the insulator being as far as practicable proof against the 25 evils of leakage, arcing and puncturing.

Other objects of my invention are the following: to provide tension members with fastening members of such form as to enable a person to attach them or remove 30 them at will: to protect from the weather a portion of the insulating member, terminal, conductor or guy as the case may be, employed in connection with the insulator: to provide an aperture within the insulator 35 adapted to detachably receive a strain member, and to form the insulator into such protective parts as will effectively prevent the entrance of moisture into the aperture, such as will also cover and protect a considerable 40 portion, if not the whole, of the strain member, which extends outside the apertures, and such as will even cover and protect the attaching eye forming part carried by the strain member, to the end that all of these 45 parts may not be subjected to the deteriorating effects of the elements, and to the end that it may be unnecessary to fill or close the unoccupied space in the aperture with cement or like material, the presence of which 50 would prevent the ready detachability of the strain member; to prevent the line wire or

guy wire from falling in the event that the insulating member or any part thereof becomes injured or destroyed: to give the various parts such form as will tend to prevent 55 leakage, arcing or puncturing, under the influence of currents of high potential and to adapt the device for application in various relations: to dispose the strain members in such relation to each other that the insulating member located between them will be subjected to a crushing action only, whenever the insulator is in actual service: and to provide an insulator possessing the highest possible form of electrical insulation 65 combined with great mechanical strength.

My invention further seeks to render the insulator unit flexible in relation to its supports, and if more than one such unit is employed, to render such units flexible to each 70 other.

Reference is to be had to the accompanying drawings forming a part of this specification, in which similar characters of reference indicate corresponding parts in both 75 figures.

Figure 1 is a view partly in section and partly in elevation, showing a pair of my improved insulators connected together and disposed vertically for purposes of supporting a line or for guying or the like; Fig. 2 is a view partly in section and partly in elevation, showing two of the insulators connected head to head and disposed horizontally for purposes of a strain insulator, for 85 dead ending or the like.

When considering two juxtaposed conductors as being insulated from each other, it is apparent that any protection afforded one of the conductors, serves equally well 90 for both. That is to say, that supplying a given, sufficient, amount of insulating material and protection to one of the conductors will prevent a flow of current between the conductors the same as if that amount of insulating material and protection were distributed to the two conductors. One of the conductors may therefore be wholly exposed, if desired, so long as the other is amply protected. I have made use of these facts in 100 devising the structure disclosed in the accompanying drawings in such wise that one

of the conductors, or strain members, which I employ, being more or less exposed and accessible, is rendered very easily detachable for exchange with others of varying lengths and capacities, or for removal in case of breakage, etc., while the other conductor, or strain member, is protected to a very high degree, not only from physical contact with the first, but also particularly against attacks of moisture and dust, with their attendant evils. The second strain member, in the structure which I have devised, is also easily detachable and readily interchangeable with others of varying lengths and capacities, though, in this instance the exchange may be subject to slightly more inconvenience than with the first, or exposed, conductor, owing to its relatively sealed disposition. The invention thus provides a structure comprising an arrangement of strain members thoroughly insulated from each other, and having the other characteristics above pointed out, which may be very easily altered to meet minor variations in existing requirements, such as are encountered in the great majority of instances; and which may be further altered in other or unusual instances. In order to accomplish these desirable and practical results I have provided a preferably substantially cylindrical body of insulating material designated as 3 on the drawings. This body is hollowed out for the greater portion of its length to form a deep, frusto-conically shaped, protective chamber 4 for the strain member 8, which shall hereinafter be referred to as the protected strain member. The remainder of the body 3 is relatively solid as at 6, though of somewhat smaller diameter than the hollowed portion 3, and the end of the solid portion is preferably rounded into hemispherical shape. Extending transversely through the relatively solid portion 6 is a straight aperture or passage 14. A U-shaped passage 7 is formed through the portion 6 having its rounded or looped portion 7^a arranged substantially concentric with the outer hemispherically shaped surface of the portion 6, and having its two legs 50 formed straight and arranged in strictly parallel relation and opening into the cup shaped or hollow portion 4 of the body, said straight legs being substantially parallel with the longitudinal axis of the body 3. The legs 7 are spaced equi-distance upon opposite sides of the transverse aperture 14 so as to dispose a considerable quantity, or bulk, of the insulating material, of which the body is formed, intermediate said legs and the aperture 14. The rounded or looped portion 7^a is substantially concentric with the center of the transverse aperture 14 though it is preferably arranged so that its inner surface is spaced a slightly greater distance from the

transverse aperture 14 than is the inner surface of the legs 7, so as to dispose a greater bulk of insulating material between itself and the transverse aperture 14 in the line of strain.

The protected strain member 8 is of a flexible material such as a wire rope or the like, and is threaded through the U-shaped passage, or aperture, 7 7^a having its two ends extending into the hollow portion 4 and connected together by a suitable clamp 10. 75 The other or exposed conductor, or strain member, is indicated by the numeral 15 and is simply passed directly through the transverse aperture or passage 14, having its opposite ends bent toward each other about 80 the hemispherical end of the part 6 and connected by a clamp 10 similar to that connecting the ends of the protected strain member. This strain member 15 is preferably also of a flexible material and, upon detachment of the clamp from its ends, it may be immediately detached from the straight, comparatively exposed, aperture 14 and be exchanged for one of greater strength, varying length, etc., as conditions may require. 90

At the point where the relatively solid portion 6 of the body 3 merges into the hollowed portion thereof, the body is formed with an annular flange or hood 5 which projects outwardly for a sufficient distance to 95 protect the exterior surface of the hollowed portion of the body 3 from direct attack of rain water, etc., and to assist the walls of the hollowed portion in protecting the protected conductor and attached metallic parts. 100 Assuming the insulator to be arranged in vertical relation, as shown in Fig. 1, the flange or hood 5 may be described as having its upper surface inclining outwardly and downwardly, and its under surface likewise 105 inclined outwardly and downwardly away from the body 3 so as to preclude the possibility of a flow of moisture toward said body. The hollowed, frusto-conically shaped, portion 4 is arranged with its smallest diameter innermost so as to prevent a flow of moisture toward the inner end thereof, and into the legs of the U-shaped aperture 7, even when the insulator is arranged in a horizontal position as shown in Fig. 2. This 110 hollowed portion being of a comparatively great length and practically inclosing the otherwise exposed portions of the protected conductor 8 from the point where it merges from the U-shaped aperture 7, forms an efficient means of excluding moisture and dust from the interstices left within the aperture by the relatively loose fit of the member 8 therein, and obviates the necessity for filling these interstices with cement, the presence of which would prevent a ready detachment and subsequent readjustment of the strain member 8. 115 120 125

The exclusion of moisture from the passage is essential as if moisture were permitted to gather in the interstices it would not only rust and therefore form a subtle 5 destroyer of the hidden portions of the conductor; but, in cold weather, it would freeze and create crevices in the insulating material through which it might flow and form a conducting path to the other strain member and 10 would ultimately fracture and destroy the insulator. These disasters are overcome by the extensive protection afforded by the relatively deep, open, hollow portion 4, within which dry air may freely circulate, and the 15 protected conductor, at the same time, is maintained readily detachable.

The clamps 10 described for connecting the loose ends of the strain or conductor members 8 and 15 are two-part clamps, having generally the form of a Y, and are provided with eyes 11. These clamps are mounted upon the ends of the strain members in such manner as to conceal the joint which is preferably made by twisting the 20 ends of the strain members together, as at 9. The eyes 11 are in pairs, and extending through each pair is a bolt 12 which holds the two parts of the respective clamp together. Each clamp provides a pocket 13, comprising the stem of the Y, while the opposite legs of the Y project outwardly therefrom, the clamp 10 holding the ends of the protected conductor 8, having its two legs arranged so as to space the exposed portions 25 of the protected conductor apart a distance corresponding to the space between the legs of the U-shaped aperture 7 in the insulator body, while the strain member 15, upon leaving the legs of its clamp 10 flares outwardly 30 along the sides of the portion 6 of the insulator body, said portion being of somewhat greater width than the clamp. This arrangement produces, in practice, a force 35 tending to crush the sides of the portion 6 toward each other, which tendency serves to assist the material of the insulator in resisting the direct pull of the strain member and prevents chipping or fracture of the material of the insulator, which might result 40 from a straight pull from the ends of the passage 14. A compression strain is set up from the material at the end portions of the openings 14, substantially in a direction toward the strain member 8, rather than a 45 shearing strain past said member 8, as would appear if the legs of the strain member 15 were arranged parallel, or were inclined in an opposite direction to that illustrated. Each of the clamps provides a pocket, in the 50 hollow of the Y, adapted to be directly engaged for supporting another insulator, or for engaging a support for the present insulator, as the case may be.

It is apparent that upon detachment of

the clamp 10 from the ends of the protected 65 strain member 8, said strain member may be detached and have substituted therefor a strain member of a different capacity or a different length, as desired. If a shorter member 8 is used, then the clamp 10 may be 70 disposed wholly within the hollowed portion 4 and will thus be more effectually protected, which arrangement may be necessary or desirable in unusual instances.

Insulators of the class disclosed herein are 75 particularly designed for use as one of a series of interlinked insulator units, such as form what is known as a chain type insulator.

It is seen that I have done away with the 80 use of separately formed connecting members for the units of my chain-type insulator. Each unit, with its two strain members is complete in itself. Each strain member comprises a closed link and a separately 85 formed part, which may be readily disconnected to open the link and which may be as readily again attached to close and lock the link and which will form a reinforced open seat within which the next unit may 90 loosely rest.

The complete insulator unit comprises the body of insulating material, a strain member 8 and a strain member 15, together with a clamp 10 upon each of these strain members. 95 Each insulator body with its accompanying parts, I consider as a unit. Any number of units may be chained up together, as indicated in Fig. 1, and used to support a line or employed in any other relation wherein it 100 is desirable to virtually add together the various insulative powers of several units. If desired, two units may be placed head to head, as indicated in Fig. 2, this arrangement being preferable where the device is 105 used for purposes of a double unit strain insulator. If desired, however, multiple units may be used for purposes of a strain insulator, as well as for other purposes.

Owing to the novel construction of my 110 strain insulator, it will be observed that for any given size of insulator body it provides the greatest possible insulating area for the prevention of surface leakage and also the tendency to arc and to puncture, thereby 115 providing a very large factor of safety.

The disposition of the tension members relatively to each other and to the insulating member is such that the insulator is entirely exempt from all but compression strains and 120 hence possesses exceptionally great mechanical strength combined with the highest possible form of electrical insulation. These insulators may be used separately or any number of them may be linked or connected together, or connected to insulators of different form, in any preferred manner, so as to 125 increase the aggregate insulation for sup-

porting a line, dead ending, guying or in any other relation where currents of very high potential are employed.

I do not limit myself to the exact form nor 5 to the details of any or all the parts above shown and described, nor do I limit myself to any particular combination of the parts; neither do I limit myself to the use of any prescribed materials, as in some instances I 10 may employ a tough insulating material such as "electrose" or I may employ a brittle insulating material such as porcelain or other brittle material, the flexibility of the links and the location of the passages 7 and 14 are 15 such that the various mechanical strains are distributed to the best advantage, so as to preserve the insulator body and also to protect the tension members.

Having thus described my invention, I 20 claim as new and desire to secure by Letters Patent:

1. In a device of the class described, the combination comprising an elongated body portion of insulating material hollowed out 25 for the greater portion of its length to form an elongated chamber longitudinally of the body having an end wall deep within the body of only slightly less diameter than the open end of the chamber, and the side walls 30 of the chamber being substantially straight and converging little, and said body having a U-shaped aperture formed in the remainder of its length arranged with two straight, substantially parallel disposed legs 35 extending longitudinally of the body, and opening through the end wall of said chamber, opposed strain members, one of which is disposed loosely in said U-shaped aperture, readily detachable therefrom, having 40 exposed end portions extending into said chamber, and being formed with means for attaching a supported conductor, the other strain member extending through an aperture formed in a straight line transversely 45 entirely through the body and through the loop defined by the U-shaped aperture, the deep chamber within the body serving to effectually protect the U-shaped aperture from moisture, whereby to avoid the necessity 50 for filling the interstices with cement or other material to exclude moisture.

2. In a chain-type insulator, the combination comprising a body of insulating material, having a U-shaped aperture formed 55 therein arranged with its two legs opening out toward one end of said body, and having a second aperture formed in a straight line transversely entirely through said body at an angle to the plane of the first aperture, 60 and through the loop defined by the first aperture, a U-shaped strain member disposed in said U-shaped aperture, a second strain member formed of flexible material threaded through the straight transverse

aperture and projecting from opposite ends 65 of said straight aperture so as to be easily detachable, said second strain member being bent at the opposite ends of the straight transverse aperture into relatively inclined 70 portions converging toward each other beyond the body, and impinging against the opposite side surfaces of the body adjacent the ends of said straight transverse aperture, and means connecting together the 75 ends of said second strain member, adapted to hold the ends in converged relation and to form an open seat for a supported conductor, the inclined relation of the end portions of the second strain member against the sides of the body, producing a compression strain from the end portions of the straight transverse aperture toward the loop part of the first strain member, whereby the body may be able to withstand heavy longitudinal strains without fracture, substantially as described. 80

3. In an insulator, a body portion of insulating material, a plurality of strain members extending therefrom in spaced relation, and separately formed U-shaped member connected by its legs to the strain members for connecting said strain members together and for providing an open seat between said strain members within which a support may loosely rest. 85

4. In an insulator, a body portion of insulating material, a plurality of flexible strain members extending therefrom in spaced relation having their ends twisted together, and a detachable clamp member 90 having a part engaging over said twisted ends to prevent their becoming untwisted and also having a U-shaped part to provide an open seat between the strain member within which a support may loosely rest. 95

5. In a chain-type insulator, a pair of insulator units spaced apart, a separately formed strain member carried by each unit extending toward the other unit, each comprising a closed link of flexible material, 100 and at least one of said closed links comprising a separately formed part of non-flexible material readily detachable for opening that link, and said separately formed part, when attached to close the 105 link, being adapted to form an open seat upon that link within which the other link may loosely engage. 110

6. In an insulator, a body portion of insulating material, a pair of flexible strain members extending therefrom in spaced relation having their ends twisted together, and a detachable Y-shaped clamp member, the stem part of the Y being in clamped engagement with the twisted end portions of 120 the strain members to retain said portions twisted, and the opposite legs of the Y extending along and being in clamped en- 125

gagement with the two strain members respectively to further retain them against disconnection from each other and also to provide an open seat between the legs of
5 the Y within which a support may loosely rest, and means for attaching a conductor to said insulator.

In testimony whereof I have signed my name to this specification in the presence of two subscribing witnesses.
